PORTABLE SERVICE CART FOR SILVERWARE AND DISHES OR THE LIKE

Delmar D. Rhoads, 3112 Oakwood Drive,
Fort Wayne, Ind.

Filed June 9, 1958, Ser. No. 51,260

Term of patent 14 years

(Cl. D14—3)

FIG. 1

FIG. 2

The side not shown is like the side shown, and the rear is substantially plain.

I claim:

The ornamental design for a portable service cart for silverware and dishes or the like, substantially as shown and described.
